UNITED STATES PATENT OFFICE

JULIA SPEXARTH, OF VANCOUVER, WASHINGTON

GIRDLE AND HOSE SUPPORT

Application filed October 15, 1926. Serial No. 141,806.

This invention relates to a lady's girdle for use as a combination abdominal support and hose support. The object of the invention is to provide a girdle which may give effective service as an abdominal support and which is so constructed as to afford a good fitting relation for any kind of dress worn on the outside of the person, to give perfect freedom to the body of the wearer and afford efficient service as a support for the hose. The girdle is constructed of multiple sections of stout flexible fabric having a much deeper web in its middle rear sections than on the wings which span the body and are locked together centrally in front by snap fasteners or hooks. The multiple sections forming the panels spanning the front of the body are connected to the wider skirt portion at the rear by elastic webbing to afford resiliency to the girdle and permit a snug fit around the hips and over the abdomen without personal inconvenience. Connected to the elastic sections at the sides are elastic tapes carrying adjusting buckles with pivotal metal guides for a loop cord attached to the body of the girdle, in the several loops of which are carried pendent hose-supporters. My invention, therefore, consists of a lady's girdle adapted to act as an abdominal support, composed of a plurality of sections of differing length and width connected by elastic webbing at its sides, with cords at the sides respectively connected with the main body of the girdle and the two wings, and a plurality of pendent hose clamps at the sides.

In the accompanying drawings illustrating the invention:

Figure 1 represents in elevation a girdle embodying my invention with a pair of hose supports at each side.

Figure 2 shows one side of the girdle with the accompanying hose clamps in triplicate for a stout woman.

Figure 3 shows the manner of applying the girdle to a wearer showing its appearance from the front.

Figure 4 is a similar view as appearing from the back of the form shown in Figure 2.

With reference more particularly now to the drawings in detail, the rear portion of the

girdle is formed of three pieces of stout fabric united by sewing at seams 1, 2, 3, 4. Along the seams of the two rear sections 1, 2 and the front edges of the wing sections 5, 6 is mounted a strip of thin elastic steel secured in place by a band of tape stitched fast. The several sections, three forming the back part and the two forming the front wings, are united together at overlapping edges of a single ply fabric by lines of stitching. The upper edge of the girdle is whipped over with lines of stitching to form a selvage edge. On the edge of one of the wings is secured a pair of metallic punched loops 7, 8, and the opposite wing is provided with coordinately positioned ball studs 9, 10 to act as fasteners. The other edges of the wings are united to the skirt section by bands of elastic webbing 11, 12. A round woven cord 13 is securely sewed one end to the right or left wings respectively, and the other end to the skirt, after having been threaded through a pair of elastic webs 14 and also through a plurality of pendent elastic tapes carrying hose clips 21. These hose supporters are arranged in duplicate at each side for a thin subject, but are arranged in triplicate, as indicated in Figure 2, for a stout subject. The hose clamps may be of standard type formed of a pivoted arched loop 19 of sheet metal to form a guide for the woven cord, and a pivoted loop 20 carrying a section of elastic tape, and a pivoted metallic slotted grip-member 21 adapted to lock the fabric of a stocking on a vulcanized button 22 sewed to a tape 23 hung on the metallic loop 24 sewed on an elastic web 25. The plurality of hose clamps are of identical construction. The garment in use is drawn about the body with the wing elements to the front and drawn taut over the abdomen and locked in position at the two vertically superposed fastenings. The pendent elastic hose clips are then clamped to both stockings and the garment is in place for efficient service.

I have thus described my invention for the best construction I have thus far provided, but it is understood that I do not limit myself to the specific details of the parts described and that minor modifications within the

meaning of my claim may be made without departing from their scope.

Having thus described my invention, what I claim as new and desire to secure by Letters Patent is:

- 5 A girdle and hose support consisting of a girdle having a downwardly extending portion at the rear thereof and having means for fastening same around the body of the wearer, in combination with two separate hose supporting cords mounted at opposite sides of the girdle each cord having its forward end secured to the lowermost front edge of the girdle and its rearward end secured at the forward lower corner of the downwardly extending portion thereof, a yieldingly slidably intermediate support for each cord between its bight and the girdle forming a plurality of cord loops, and a hose supporting fastener 10 15 20 slidably mounted at each cord loop between the supports at each side of its loop.

In testimony whereof I affix my signature.

JULIA SPEXARTH.
